(57) **CLAIM**

The ornamental design for a footwear securing device, as shown and described.

DESCRIPTION

FIG. 1 is a Perspective view of the footwear securing device, shown in use wherein the environment is shown in broken lines and forms no part of the design.

FIG. 2 is a Perspective view of the thereof, shown in isolation.

FIG. 3 is a Front elevational view thereof, the Rear view being its mirror image.

FIG. 4 is a Right Side elevational view thereof, the Left Side elevational view being its mirror image.

FIG. 5 is a Top End view thereof; and,

FIG. 6 is a Bottom End view thereof.

The broken lines in FIGS. 1-4 depict unclaimed subject matter and form no part of the claimed design.

1 Claim, 6 Drawing Sheets
